TRANSFORMER

Wilmer J. Leidy, Chicago, Ill., assignor to Chicago
Transformer Corporation, Chicago, Ill., a cor-
poration of Illinois

Application August 28, 1936, Serial No. 98,289

1 Claim. (Cl. 171—119)

This invention relates to transformers and particularly to small transformers having all the leads thereof coming out of one end. Transformers of this type, such as, for example, power supply transformers for radio receivers are usually mounted vertically on a chassis pan. A suitable aperture is stamped out of the pan and a portion of the transformer including the wiring leads extends below the top of the chassis pan and into the interior thereof. The transformer is bolted in this fashion and usually presents a clean exterior unbroken by any wiring.

In the case of radio receivers—and, in fact, in any electrical device employing transformers—the occasion frequently arises when the transformer ratio must be varied. While 110 volts, 60 cycles is the usual standard in this country, there are numerous and varied voltages in other parts of the world. In a case of this character, particularly where it is desired to export radio receivers of other articles employing a transformer, it is desirable from a production standpoint to employ a universal type of transformer which may be mounted in the apparatus and connected in the usual manner. In the event that the transformer ratio must be changed to take care of different voltages, it is desirable that some simple method be available for accomplishing the above. In order to avoid service difficulties, and in order to make it possible for a lay-man to accomplish this, it is necessary that this method be simple and fool-proof. Furthermore, it is necessary that this method be economical. In addition, it is desirable that the change be effected from the exterior of the aperture rather than from any interior, portion thereof. In the case of a radio receiver, the maze of wiring in the chassis pan is such as to preclude the possibility of a fool-proof and effective change. Furthermore, by making it possible to make the change from the exterior of the apparatus, it is evident that just prior to final checking, when the radio receivers or other devices are stacked, a person can simply go over the various units and make the necessary changes without turning over of any of the units.

Referring to the drawing, Figure 1 is an illustration of a transformer employing this invention. Figure 2 is a plan view looking down upon this same transformer. Figure 3 is a detail of the switching means. Figure 4 is a circuit diagram of the transformer.

Referring to the drawing, a pair of pressed steel end shields or bells 1 and 2 are shown. Between these is a stack of laminations 3 enclosing a plurality of windings. The transformer is mounted

upon a suitable base 5. The transformer laminations are clamped together and the entire transformer structure is supported on base 5 by means of bolts 10 and nuts 11. The windings of the transformer have a plurality of leads 12 to 20 inclusive, for outside connection, projecting through suitable apertures in the bottom of bell 2.

As shown in Figure 4, the transformer windings comprise a primary 24 and a secondary 25. Primary 24 has a plurality of taps 26 to 30 inclusive and end connections 12 and 31. Wires 26 to 31 inclusive are taken out through top bell 1. Bell 1 has an opening 35 in the top thereof covered by an insulating plate 36 riveted at 37 and 38 thereto. Plate 36 carries a plurality of pins 40 to 45 inclusive disposed in a circle over bell opening 35. A pin 36 is disposed in the center thereof.

It will be noted that pin 46 is longer than the remaining pins.

Leads 26 to 31 inclusive from the transformer primary are connected to pins 40 to 45 inclusive. A connector lead 13 extends from the bottom of the transformer therethrough to the top and is connected to center pin 46.

To provide a selective switching action, a rotary socket member is provided. This consists of an insulating disk 48 having a series of apertures 49 to 54 inclusive adapted to register with pins 40—45. A central aperture 55 is provided to register with center pin 46. Superposed above disk 48 is a smaller insulating disk 56 having apertures 49 to 55 inclusive. The two disks are retained together by an eyelet 57 passing through central aperture 55 in both disks. Disposed in any one of outer apertures as 50 is a contact 58 adapted to receive any one of the pins 40—45. A similar contact 59 is carried by eyelet 57 at the center aperture and is adapted to receive center pin 46. Contacts 58 and 59 are connected together at 60. A cap 61 of metal is adapted to cover the entire switching means and is retained by upper disk 56 by means of ears 62. Disk 56 is cut away at 63 to clear ears 62 to permit cap 61 to be turned on or off.

An arrow is marked on lower disk 48 at aperture 50 to indicate the contact position. Various numbers may be stamped on insulating member 36 at the various pin positions to indicate the voltages. It is obvious that the transformer ratio may be changed by pulling up the socket member in the position shown in Figure 3, rotating same on the center pin and then pressing down at the desired position.

This is an improvement on Patent 1,988,733 granted January 22, 1935.

What is claimed is:

A transformer comprising a stack of laminations and a plurality of windings, each winding having at least two terminal leads and at least 5 one winding having a plurality of intermediate tap leads, an insulating disk carried by said transformer, a plurality of pins carried by said disk and arranged on the circumference of a circle, means for connecting said tap leads and one terminal of 10 said one winding to said pins, a pin carried by said disk at the center of said circle, a lead connected to said central pin and constituting a terminal connector for said one winding, a second disk having apertures therethrough registering with all

the pins on said first disk, a connecting member disposed in the center aperture and in one of the circularly disposed apertures of said second disk, said second disk being adapted to be telescoped down over the pins of said first disk with the connecting members of said second disk connecting the central pin and one other pin, a cap carried by said second disk and clearing all pins and forming a protecting cover thereover, said central pin being longer than the remaining pins whereby 5 said second disk may be pulled up by holding said cap and rotated to provide a connection between the central pin and any one of the other pins. 10
